United States Patent

Des. 235,433
Patented June 17, 1975

235,433

WHEEL CENTER

Joseph R. May, Chatham, and Donald F. Morgan, Bloomingdale, N.J., assignors to Amerace Corporation, New York, N.Y.

Filed Feb. 13, 1974, Ser. No. 442,150

Term of patent 14 years

Int. Cl. D12—76

U.S. Cl. D12—211

Figure 1

Figure 3

Figure 2

Figure 4

Figure 5

FIG. 1 is a front elevational view of a wheel center showing our new design;

FIG. 2 is a rear elevational view thereof;

FIG. 3 is a sectional view thereof taken along the line 3—3 of FIG. 1;

FIG. 4 is a fragmentary sectional view thereof taken along the line 4—4 of FIG. 1; and

FIG. 5 is an enlarged fragmentary sectional view thereof taken as indicated by the broken line 5 in FIG. 3.

The broken lines in the drawing are for illustrative purposes only.

We claim:

The ornamental design for a wheel center, substantially as shown and described.
